UNITED STATES PATENT OFFICE.

JAMES LOGAN, OF CARTHAGE, MISSOURI.

BOX-CAP HANGER FOR GANG-FRAMES OF STONE-SAWING MACHINES.

1,151,698.

Specification of Letters Patent. Patented Aug. 31, 1915.

Application filed February 17, 1915. Serial No. 8,843.

To all whom it may concern:

Be it known that I, JAMES LOGAN, a resident of and whose post-office address is Carthage, Missouri, have invented a new and useful Improvement in Box-Cap Hangers for Gang-Frames of Stone-Sawing Machines, which invention is fully set forth in the following specification.

This invention relates to an improvement in gang frames for stone-sawing machines, and more particularly to the box cap hangers employed to support the gang frames. In machines of this character, it is usual to support the extremely heavy gang frames for the stone-saws upon the framework of the machine by means of depending hanger bars, which bars are mounted to swing pendulum-like in the framework of the machine, and the heavy gang-saw frame is pivotally connected to the lower end of said hanger bars. By reason of the great weight of the gang frame and its supported saws, and the fact that they are almost continuously operated under conditions where grinding sand and grit from the sawn stone gets into the bearings, the pivotal bearing connections between the gang-saw frame and the lower end of the hanger bars wear away very rapidly, and necessitate frequent adjustments to preserve the parts in proper working order, and such adjustments have heretofore required a considerable amount of time, owing to the necessity of disassembling the hanger box cap and the insertion of wear pieces or the employment of other devices to take up the wear.

The particular object of the present invention is to provide a hanger box cap, so called, in which the pivotal bearings connecting the saw gang frame to the hanger bars shall be protected as much as possible from the entrance of abrasive material, which would cause rapid wear of the parts, and furthermore, to provide means for quickly and effectively adjusting the parts to take up wear without disassemblage. By the present invention, this adjustment is accomplished in a very few moments, so that the interruption of the active work of the machine is comparatively short.

The inventive idea involved is illustrated in the accompanying drawings, in which—

Figure 1 is a perspective view of one embodiment of the invention; Fig. 2 is a central vertical section with parts shown in elevation; Fig. 3 is a bottom plan view of

the upper portion of the box cap; and Fig. 4 is a perspective view of one part of the device for adjustment to take up wear.

Referring to the drawings, in which like reference numerals indicate like parts throughout the several views, 1 is the depending hanger bar of the usual or any suitable construction in a stone sawing machine, and 2 is one corner portion of the gang saw frame, to which there is bolted a trunnion bracket 3 projecting vertically upward therefrom, and having a trunnion 4 extending horizontally therefrom, as clearly shown in Fig. 2. Secured by the bolts 5, 5, to the lower end of the hanger bar 1 is the upper or cap portion 6 of the hanger box. This cap portion of the box is shown in perspective in Fig. 1, in section in Fig. 2, and in bottom plan view in Fig. 3. Formed in the upper portion of the cap 6 is a groove 7 extending parallel with the trunnion 4 when the parts are assembled, and the roof or upper portion of the groove 7 is formed on a downward incline from one end thereof to the other. This groove 7 extends in the cap 6 for approximately the length of the trunnion 4, and there is formed within the cap 6, to the left of the groove, as shown in Fig. 2, a chamber 8 opening downward, while the left-hand wall of this chamber has formed therein a vertical slot 9, for a purpose which will be hereinafter described.

The cap portion 6 of the hanger box has oppositely disposed lateral lugs 10, 10, with vertical perforations therethrough, and the lower portion of the hanger box 11 has formed thereon corresponding lugs 12, 12, also having vertical perforations therethrough, said lower portion having formed therein a concave bearing surface 13 constituting the bearing proper for the trunnion 4, on the bracket 3. The trunnion being placed in position, the two parts of the hanger box are bolted together by means of bolts 14, 14 (Fig. 1), extending through the respective lugs 10 and 12 on the two parts of the box, with a wedge-shaped block 15 having a lower concave surface 16 (Fig. 4) resting upon the trunnion 4, and an upper surface 17 downwardly inclined and resting in contact with the downwardly inclined roof of the groove 7. Securely connected to the block 15 is a rod 18, which extends outward through the chamber 8 and through the slot 9 formed in the cap 6, and this rod 18 has formed on its end portion screw-threads for

receiving nuts 19 and 20 by means of which the rod 18, and therefore the block 15 which forms the upper bearing surface for the trunnion 4, is locked in position.

5 It will be observed that the parts are protected from any foreign matter falling into the bearings from above by reason of the construction of the cap 6. In case of a 10 wearing of the parts, and particularly of the trunnion 4 and of the bearing 13 therefore, such wear may be quickly and effectively taken up by loosening the nut 20 and tightening up the nut 19, after which the nut 20 will be again tightened, and the machine 15 is then ready to be set into operation again. During the tightening operation, as the block 15 is moved from right to left in Fig. 1, and by reason of the wear on the trunnion and the trunnion bearing 13, the 20 level of the block 15, and therefore of the rod 18, will be lowered, and the slot 9 in the left-hand end of the cap 6 provides for this lowering movement of the rod and the block 15 throughout the several adjustments 25 that may be necessary during the life of the trunnion and the trunnion bearing 13.

In the act of adjusting the position of the adjusting block 15, the nut 20 can be reached from below, while nut 19, of course, is 30 readily reached from the outside.

It has been found in practice that this means of protecting the trunnion bearings from undue wear and taking up the wear when the same occurs is most efficient, and 35 that it materially prolongs the life of the parts, and enables proper adjustments, when necessary, to be made in a minimum space of time.

What is claimed is:—

40 1. In a box cap hanger for gang-saw frames for stone-sawing machines, the combination of a hanger-bar, a hanger-box cap secured thereto and having a groove formed in its top wall, said groove having its upper 45 surface portion downwardly inclined, a gang-saw-frame trunnion, a bearing for said trunnion secured to said cap, a bearing block resting on said trunnion and having its up-

per surface engaging the inclined surface of said groove, a rod secured to said block and 50 extending outward through a slot in said cap, and adjusting means exterior to the said cap and engaging said rod.

2. In a box cap hanger for gang-saw frames for stone-sawing machines, the combination of the box-cap and the lower bearing secured thereto, with the trunnion resting in said lower bearing, an upper bearing block resting on said trunnion and movable 55 parallel with the axis of said trunnion in a downwardly inclined groove formed in the upper wall of the cap, a rod secured to said block and extending out through the wall of said cap, and adjusting means exterior to said cap and engaging said rod.

3. In a box cap hanger for gang-saw frames for stone-sawing machines, the combination of the box-cap and the lower bearing secured thereto, with a gang-saw-frame trunnion resting in said lower bearing, a 70 wedge-shaped block having its lower side concaved to fit said trunnion and its upper side downwardly inclined and contacting with a correspondingly inclined surface in said cap, a screw-threaded rod secured to 75 said block and extending out through a vertical slot in the cap, and nuts on said rod on opposite sides of the wall of said cap.

4. In a device of the character described, the combination of the cap having an interior chamber opening downward and a 80 downwardly inclined groove formed on the inner side of the roof portion thereof, a trunnion, a wedge-shaped block movable in said groove and forming the upper bearing 85 for said trunnion, a lower bearing for the trunnion, and means on the exterior of the cap for adjusting the block in said groove.

In testimony whereof I have signed this specification in the presence of two subscribers. 90

JAMES LOGAN.
